UNITED STATES PATENT OFFICE.

OTTAR S. LEE, OF CHICAGO, ILLINOIS, ASSIGNOR TO THE NYE TOOL & MACHINE WORKS, A CORPORATION OF ILLINOIS.

VISE.

Application filed March 26, 1926. Serial No. 97,628.

My invention relates to vises of the type comprising a base presenting a portion against which the article, as for example a pipe, to be clamped, is seated, a flexible element by which the article is clamped in the vise, and means for tightening the element against the article; my primary object being to provide a novel, simple, inexpensive, and durable construction of vise of the type referred to and one by which the flexible element may be quickly rendered taut or loose, at will, and which will require the exertion of a relatively slight amount of force only by the operator.

Referring to the accompanying drawings:—

Figure 1 is a plan view of a vise embodying my invention, the handle portion, the flexible element of the device and a portion of the tauting means, being omitted. Figure 2 is a view in vertical sectional elevation of the complete device with certain of the parts shown in elevation, the section being taken at a line corresponding with the line 2—2 on Fig. 1 and viewed in the direction of the arrows, this view showing a pipe clamped in place in the device; and Figure 3. an end view of the device, the device being viewed from the left-hand side of Fig. 2.

The preferred illustrated embodiment of my invention comprises a base 4 at which the device is adapted to be secured to a support, as for example to the top of a table, as by bolts 5 passing through openings 6 in the base 4. The base 4 is shown as formed integrally with upwardly extending parallel, spaced apart, plate portions 7 integral with the bottom plate portion 8 of the base 4 and connected together by an angular web 9 rising from the plate portion 8 with its portion 10 extending generally parallel with the plate portion 8 and presenting a slot 11 in its outer end. The plate portion 8 in alignment with the space between the plate portions 7 is slotted, as represented at 12, with a web portion 13 connecting together the ends of the plate portions 7.

The outer faces of the plate portions 7 are recessed, as represented at 7^a, to receive jaw members 14 secured thereto as by the bolts 15 and presenting toothed seating surfaces 14^a at which the article, as for example

the pipe shown at 16, to be clamped in the vise, bears.

Located in the space between the plate portions 7 and directly below the web portion 13, is a rock lever 17 pivotally supported at one end, as represented at 18, to the plate portions 7 and provided at its free end with a head 19, the under surface of which, and represented at 20, is semi-cylindrical.

The device also comprises a flexible element 21, shown as a chain, for clamping the article, as for example the pipe 16, firmly against the bearing surfaces 14^a, one end of this chain being adapted to be introduced into the recess 11 to interlock at one of the cross pins 22 of the chain, with the arms 23 of the web portion 10 located at opposite sides of the recess 11. The other end of the chain which passes over the object 16 as shown in Fig. 2, extends beneath, and in engagement with the head 19 and connects at 24 its extremity with the lever 17 between the head 19 and the pivot 18, as by means of the pivot pin 24.

It will be understood from the foregoing that by arranging the parts as described, pressure exerted downwardly against the lever 17, preferably at its head portion 19, which operates to swing this lever in counterclockwise direction in Fig. 2 operates to pull downwardly on the free end of the chain and thereby tightly grip the object 16 against the bearing surfaces 14^a and by reason of the leverage action thereby afforded against the free end of the chain, a relatively slight amount only of such pressure is required to exert a powerful clamping action against the object 16, it being noted that wear on the chain at the portion thereof engaged by the head 19 is practically negligible because of the absence of friction between these parts. Any suitable means for actuating the lever 17 may be provided, those shown comprising an actuating threaded rod 25 which has screw threaded engagement with an opening 26 in the web 13, the outer end of this rod being equipped with a handle for operating it, shown preferably as a forked member 27 pivotally supported at inwardly extending projections 28 on the arms 29 thereof, in diametrically opposed openings 30 in the outer head portion 31 of the rod, this construction permitting the handle 27

to be turned down to a position in which it extends at an angle to the rod 25, permitting the operator to exert a relatively great leverage for the turning of the latter which is disposed in such a position that when it is screwed into the web 13 it engages the upper side of the head 19 rocking the lever 17 downwardly.

While I have illustrated and described a particular construction embodying my invention, I do not wish to be understood as intending to limit it thereto as the same may be variously modified and altered without departing from the spirit of my invention.

15. What I claim as new, and desire to secure by Letters Patent is:

1. A vise comprising a base having a seating surface for the article to be clamped, a flexible element for clamping the article 20 against said seat, and means for moving said element to clamping position comprising a rock lever to which the free end of said element is connected, said lever having a portion engaging said element between the point of connection of said element with said lever and the opposite end of said element, and means engaging said lever for rocking the latter in a direction to tighten said element.
2. A vise comprising a base having a seating surface for the article to be clamped, a flexible element for clamping the article 25 against said seat, and means for moving said element to clamping position comprising a rock lever to which the free end of said element is connected, said lever having a portion engaging said element between the point of connection of said element with said lever and the opposite end of said element, and means engaging said lever for rocking the latter in a direction to tighten said element.
3. A vise comprising a base having a seating surface for the article to be clamped, a flexible element for clamping the article 30 against said seat, and means for moving said element to clamping position comprising a rock lever to which the free end of said element is connected, said lever having a portion engaging said element between the point of connection of said element with said lever and the opposite end of said element, and a screw device engaging said lever for rocking the latter in a direction to tighten said element.
4. A vise comprising a base having a seating surface for the article to be clamped, a flexible element for clamping the article 35 against said seat, and means for moving said element to clamping position comprising a rock lever to which the free end of said element is connected, said lever having a portion engaging said element between the point of connection of said element with said lever and the opposite end of said element, and a screw device engaging said lever at the free end thereof for rocking the latter in a direction to tighten said element.
5. A vise comprising a base having a seating surface for the article to be clamped, a flexible element for clamping the article 40 against said seat, and means for moving said element to clamping position comprising a rock lever to which the free end of said element is connected, said lever having a portion presenting a rounded surface at which said lever engages said element between the point of connection of said element with said lever and the opposite end of said element, and means engaging said lever for rocking the latter in a direction to tighten said element.
6. A vise comprising a base having a seating surface for the article to be clamped, a flexible element for clamping the article 45 against said seat, and means for moving said element to clamping position comprising a rock lever to which the free end of said element is connected, said lever having a portion presenting a rounded surface at which said lever engages said element between the point of connection of said element with said lever and the opposite end of said element, and a screw device engaging said lever for rocking the latter in a direction to tighten said element.

tion engaging said element between the point 50 of connection of said element with said lever and the opposite end of said element, and means engaging said lever at the free end thereof for rocking the latter in a direction to tighten said element.

4. A vise comprising a base having a seating surface for the article to be clamped, a flexible element for clamping the article 55 against said seat, and means for moving said element to clamping position comprising a rock lever to which the free end of said element is connected, said lever having a portion engaging said element between the point of connection of said element with said lever and the opposite end of said element, and a screw device engaging said lever at the free end thereof for rocking the latter in a direction to tighten said element.

5. A vise comprising a base having a seating surface for the article to be clamped, a flexible element for clamping the article 60 against said seat, and means for moving said element to clamping position comprising a rock lever to which the free end of said element is connected, said lever having a portion 65 engaging said element between the point of connection of said element with said lever and the opposite end of said element, and a screw device engaging said lever at the free end thereof for rocking the latter in a direction to tighten said element.

6. A vise comprising a base having a seating surface for the article to be clamped, a flexible element for clamping the article 70 against said seat, and means for moving said element to clamping position comprising a rock lever to which the free end of said element is connected, said lever having a portion 75 presenting a rounded surface at which said lever engages said element between the point of connection of said element with said lever and the opposite end of said element, and means engaging said lever for rocking the latter in a direction to tighten said element.
